UNITED STATES PATENT OFFICE.

THOMAS F. WELCH AND FRANK A. REYNOLDS, OF GENEVA, NEW YORK, ASSIGNEES,
BY MESNE ASSIGNMENTS, TO NONAK STROPPER COMPANY, INC.

SHARPENING MECHANISM.

Application filed October 10, 1921. Serial No. 506,840.

To all whom it may concern:

Be it known that we, THOMAS F. WELCH and FRANK A. REYNOLDS, both citizens of the United States of America, residing at 5 Geneva, in the county of Ontario and State of New York, have invented certain new and useful Improvements in Sharpening Mechanism, of which the following is a specification.

10 This invention relates to a sharpening mechanism, having to do more particularly with sharpening razors both of the safety type and the old type, and is a division, in part, of application filed March 28, 1921, 15 Serial No. 456,439.

The principal purpose of the construction set forth in this application is to afford a mechanically operated sharpening member of the rotary or oscillatory type, 20 in which a blade is acted upon in a manner similar to that of a hand stropping operation, where the strop yields and bends slightly against the pressure of the razor as the latter is drawn across it.

25 A further object is to afford a practical and efficient mechanism that enables quickly sharpening a razor of any type, and in such a way that the edge acquired will be retained for a maximum length of time.

30 The invention also comprehends further detailed improvements, all of which will appear from the following description in conjunction with the accompanying drawing, the novel characteristics being pointed out in the claims following the specification.

In the drawing:

Figure 1 is a vertical sectional view of a mechanism embodying a preferred form of the invention;

40 Figure 2 is a transverse vertical sectional view taken centrally of the machine and showing a blade in operative engagement with the sharpening member, and

45 Figure 3 is a transverse vertical sectional view on the line 3—3 of Figure 1.

The construction shown comprises a housing 1, within which is arranged a razor oscillating means including a spindle 2 to which is attached a razor support 3. The 50 razor support 3 is open at one end to receive a razor, which is inserted endwise through an opening 4 in the housing when the parts are in the position shown in Figure 3.

55 The razor support 3 is oscillated by a

crank 5 fixed upon a sleeve 6 which carries a pinion 7, the latter being frictionally engaged with the razor support 3 through a disk 8 of fibrous material such as felt located between the pinion 7 and the metal 60 friction disk 9 carried by the razor support.

The razor sharpening member includes a rotary carrier, preferably consisting of a drum 10 journalled on a spindle 11, said drum being actuated by a gear 12 which is 65 driven from the aforementioned pinion 7 through an intermediate idler pinion 13, as fully set forth in the co-pending application to which reference has previously been made.

70 By turning the operating crank 5 in one direction, it has the effect, initially, of turning the razor support 3 until the razor is engaged with the sharpening member, and therefore cannot turn any further in the same direction. Further turning of the operating crank 5 in the same direction causes rotation of the sharpening member, while the blade is engaged therewith, and upon reversing the direction of rotation of the 75 crank 5, the razor carrier is oscillated until the blade is in its opposite position in engagement with the sharpening member and the latter is rotated in the opposite direction to that first described. The construction 80 and operation of the sharpening member, which constitutes the subject matter of the present application, will now be described.

75 Arranged on the aforementioned drum 10, there is preferably a thickness of felt 85 or similar resilient material indicated at 14, and 15 is a thickness of sharpening material, such as leather. The leather or other sharpening material 15 is preferably in the form of an integral cylindrical piece which 90 is attached to the carrier at spaced points, preferably opposite to each other. In the structure shown, the leather cylinder 15 is attached to the felt material at the opposite points 16 and 17. The sharpening material may be attached to the drum or carrier in any suitable manner, as by cementing it to the resilient body 14, and it is of sufficient length to afford a slight looseness between the points of attachment so that 95 as the drum is rotated against a blade, a fullness or bulge is created in the sharpening leather behind the blade. The result of this is to afford the proper resiliency and 100 flexibility in the leather to create a maxi- 110

imum sharpening effect, the manner of cooperation between the razor and sharpening leather being practically the same as that produced by drawing a razor over a strip 5 of leather held manually.

While the sharpening material or leather has been described as attached to the carrier at opposite points, this is not essential, as the cylinder of leather or other sharpening material may be attached to the carrier at only one point, or it may be arranged loosely on the drum or carrier, so long as the leather cylinder is sufficiently larger than the drum or carrier to create a bulge or 15 thickness in the leather as the drum is rotated against a blade.

In order to impart a diagonal action between the blade and leather during the sharpening operation, the sharpening material or leather 17 is provided with a spirally arranged knife engaging portion 18 which is preferably formed by a groove 19 formed in the exterior surface of the leather and extending spirally therearound.

25 The novel features of the sharpening means herein disclosed are applicable to many types of sharpening mechanisms, and the invention is not confined to razor sharpening machines or to the precise structure 30 set forth, but may be modified in different ways and applied to mechanisms for sharpening other tools and instruments without departing from the underlying features of the improvements as defined by the following 35 claims.

We claim:

1. A sharpening member comprising a rotary carrier, and a cylinder of sharpening material surrounding and attached to the 40 carrier along lines spaced circumferentially thereof, the sharpening material being free from the carrier intermediate said spaced lines of attachment, and having sufficient fullness therebetween to afford a slight 45 bulge in the sharpening material as the carrier is rotated in engagement with a blade.

2. A sharpening member comprising a rotary carrier, a thickness of resilient material

attached to the carrier, and a thickness of sharpening material attached to said resilient material at spaced points, the sharpening material being free from the resilient material between said spaced points and of such length as to afford a slight bulge in the sharpening material when the carrier is 55 rotated against a blade.

3. A sharpening member comprising a rotary carrier, a thickness of resilient material surrounding and attached to the carrier, and a thickness of sharpening material surrounding the resilient material and attached thereto at opposite points, the sharpening material being free from the resilient material except at such opposite 60 points of attachment and of such length as to afford a slight bulge in the sharpening material between said points of attachment when the carrier is rotated in engagement with a blade.

4. A sharpening member comprising a 70 rotary carrier, and an integral cylindrical piece of sharpening material attached to the carrier at spaced points, the sharpening material having a spiral groove formed exteriorly to afford a spirally arranged knife 75 engaging portion, and being free from the carrier intermediate said spaced points of attachment and of such length as to afford a bulge in the sharpening material as the carrier is rotated in engagement with the 80 blade.

5. A sharpening member comprising a rotary cylindrical carrier, and a cylindrical piece of sharpening material surrounding the carrier and attached thereto along a 85 line extending lengthwise of the carrier, the sharpening material being free from the carrier except along said line of attachment, and having sufficient fullness to afford a slight bulge as the carrier is rotated in engagement with a blade.

In witness whereof, we have hereunto signed our names.

THOMAS F. WELCH.
FRANK A. REYNOLDS.
